UNITED STATES PATENT OFFICE.

ARTHUR F. TAYLOR, OF KAMAPOLIS, NORTH CAROLINA.

KIER SOLUTION CONTROLLER.

Application filed July 7, 1925. Serial No. 41,978.

This invention relates to kiers for bleaching cloth.

Heretofore it has been proposed to provide kiers in which the liquor is forced 5 through the central pipe upwardly and then down upon the cloth so that the liquor will come in contact with the air and then force through the cloth causing packing of the materials so that when the materials are 10 removed they will contain air, steam and rust and kier stains.

An object of the invention is the provision of a kier in which the liquor is forced in by live steam at the bottom and then through 15 a controlling pipe so that the liquor is blown through the cloth in the bottom of the kier to the extreme top and whereby the solution does not come in contact with the air before saturating the materials.

20 A further object of the invention is the provision of a kier in which the solution is forced through the cloth in concentrated condition so that the materials are not packed tight.

25 A still further object of the invention is the provision of a kier in which the solution is so controlled when delivered to the materials that it will be maintained out of contact with the air and thereby prevent cooling 30 of the solution, the solution being forced upwardly and through the cloth thereby aiding at all times in preventing the settling or packing of the materials which tends to cause channel streaks, stains and spots in 35 the materials.

This invention will be best understood from a consideration of the following detailed description, in view of the accompanying drawings forming a part of the 40 specification; nevertheless it is to be understood that the invention is not confined to the disclosure, being susceptible of such changes and modifications which shall define no material departure from the salient 45 features of the invention as expressed in the appended claims.

In the drawing:

The figure in the case shows a vertical section of a kier constructed in accordance 50 with the principles of my invention.

Referring more particularly to the drawings, the kier comprises a boiler 10 having a bottom 11 and a cover 12 hinged at 13 on the boiler. A latching mechanism 14 is employed at a diametrically opposite point on 55 the cover for locking the same to the boiler.

The bottom 11 is elevated from the lower end of the boiler and is provided with a perforation which receives an inlet pipe 15. This pipe is threaded at its inner end to receive a nut 16 for locking the pipe in position on the bottom of the kier. A pipe 17 is connected by means of a joint to the pipe 15 and is adapted to supply the solution to the boiler by the operation of the valve 18. 60 A discharge pipe 19 is likewise connected to the pipe 15 and is controlled by means of a valve 20 for permitting discharge of the solution from the boiler. 65

A block 21 is secured by means of bolts 70 22 to the bottom 11 of the boiler and is provided with a central passage 23 which is aligned with the pipe 15. The block is also provided with a plurality of radial passages 24 placing the lower chamber 25 in communication with the central passage 23 of 75 said block.

A steam nozzle 26 is mounted centrally of the passage 23 in the block and has its upper end disposed within a perforated cylinder 80 27 which forms the controller for admitting the solution to the material to be treated. The nozzle is connected by means of an elbow and pipes 28, 29 and 30 to a pipe 31 which is in communication with a source 85 of steam under pressure and controlled by a valve 32.

An internally threaded nut 33 is screwed to the top of the block 21 and is provided with a boss 34 adapted to receive a passage 90 in a false bottom 35 which has perforations 36. The bottom has a depending flange 37 in engagement with the inner wall of the boiler 10 and the portion of the bottom 35 adjacent the central passage is supported by 95 the nut 33.

The kier solution controller is in the form of a cylinder designated by the numeral 27 and is provided with a plurality of perforations 38 spaced at various heights along the 100 cylinder. The cylinder is provided with a top 39 for closing the upper end, the lower end being threaded into the nut 33 and receiving the nozzle 26 in communication with the steam pipe 31. 105

The boiler is provided with a plurality of legs 40 having feet 41 which may be secured to the floor of a building so that the boiler is spaced from the floor to provide for the insertion of the pipes 15 and 30. 110

The operation of my device is as follows: The materials to be treated are placed in

the upper chamber 42 of the boiler and supported by the perforated false bottom 35. The valve 18 is then opened to permit the hot solution to be admitted to the chamber 25 from the pipe 15 and through the radial openings 24 until the solution reaches a predetermined level in the boiler. Steam under pressure is admitted through pipe 31 by opening valve 32 and as the steam is forced 10 from the nozzle 26 the solution is carried upwardly and forced through the perforations 38 in the controlling tube 27 thereby causing the solution to be forced upwardly through the materials. By this means the 15 solution not only saturates all portions of the materials and is maintained in circulation but the materials themselves are forced slightly upwardly by reason of the solution being discharged from the perforation 38 at 20 various levels so that the packing of the materials is prevented in the boiler.

What I claim is:

1. A kier comprising a boiler having a block provided with radial passages and a 25 central passage, a pipe connected with the central passage at its lower end for supplying a kier solution, a perforated controlling tube connected with the top of the block and alined with the passage in said block, and a 30 nozzle connected with a source of steam projecting into the lower end of the controlling tube, a perforated false bottom located intermediate the ends of the boiler, a nut having threaded engagement with the lower end 35 of the controlling tube and secured to the block.

2. A kier comprising a boiler having a block provided with radial passages and a central passage, a pipe connected with the central passage at its lower end for supplying a kier solution, a perforated controlling tube connected with the top of the block and alined with the passage in said block, and a nozzle connected with a source of steam projecting into the lower end of the controlling tube, a perforated false bottom located intermediate the ends of the boiler, a nut having threaded engagement with the lower end 40 of the controlling tube and secured to the block, 45 said controlling tube extending above the false bottom, the false bottom being supported by the nut.

3. A kier comprising a boiler having a block mounted on its bottom, said block having a central passage and radial passages 55 connecting the central passage with the interior of the boiler, a perforated false bottom mounted on and supported by the upper end of the block thereby dividing the boiler into an upper and lower chamber, a tube connected with the block and alining with the central passage at a point on the block where the perforated false bottom is supported by said block, said tube being perforated and having its upper end closed and located 60 within the upper chamber.

ARTHUR F. TAYLOR.
